UNITED STATES PATENT OFFICE.

JOHN L. KOONTZ, OF HELENA, MONTANA TERRITORY.

COMBINATION-TOOL.

SPECIFICATION forming part of Letters Patent No. 374,602, dated December 13, 1887.

Application filed July 5, 1887. Serial No. 243,436. (No model.)

To all whom it may concern:

Be it known that I, JOHN L. KOONTZ, a citizen of the United States, residing at Helena, in the county of Lewis and Clarke and Territory 5 of Montana, have invented certain new and useful Improvements in Combination-Tools; and I do declare the following to be a full, clear, and exact description of the invention, such as will enable others skilled in the art to 10 which it appertains to make and use the same, reference being had to the accompanying drawings, and to the letters and figures of reference marked thereon, which form a part of this specification.

15 Figure 1 of the drawings represents a perspective view of the combined tool embodying my invention. Fig. 2 represents a side elevation and partial section of the same.

20 My improvement is more especially designed as a cigar-box scraper, opener, and closer.

25 This new article of manufacture consists of a hammer, a claw, a scraper, and a bladed opener all formed from one piece of metal, as will be hereinafter fully described, and set forth in the claim.

30 In the drawings, A represents the combined tool. It comprises a solid piece of metal bent into a ring or annulus and its ends straightened out into a shank, to which the handle 1 is attached.

35 2 is the hammer, formed at one point of the ring's periphery and extending radially outward therefrom.

3 is a claw formed at a point preferably opposite the hammer.

4 is a segment-shaped cutting-edge or scraper extending from the hammer to the claw.

5 is an opener or inserting blade formed opposite the handle 1 and on the opposite edge from that of the scraper.

40 The ring A is bent or convexed outwardly upon the side to which the opener 5 is formed, in order to provide an effective leverage power when desired.

The scraper 4 is used to efface cigar-box 45 stamps, or for other kindred purposes.

The ring-shaped form of the tool is essential, in order that the several tools formed thereon may be properly effective. In the use of the claw, for instance, it is necessary to give the 50 tool considerable throw or oscillation, and the rapid recedence of the ring from the claw on both sides thereof admits of the tool being used with facility. In like manner it will be obvious that the other tools formed upon the ring 55 are ingeniously placed for effective action.

What I claim as new, and desire to secure by Letters Patent of the United States, is—

As a new article of manufacture, a single metal bar formed into a ring and its ends into 60 a shank, said ring having on its outer edge opposite the handle a projecting lip, a curved cutting-edge formed on the opposite outer edge substantially at right angles to the lip, a hammer formed at one end of the cutting-edge, 65 and a claw at the other end thereof, all of said elements being formed of a single piece of metal.

In testimony whereof I affix my signature in presence of two witnesses.

JOHN L. KOONTZ.
